UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

CONVERTIBLE BOX-CAR.

1,398,675.

Specification of Letters Patent. Patented Nov. 29, 1921.

Application filed March 10, 1921. Serial No. 451,409.

To all whom it may concern:

Be it known that I, ARGYLE CAMPBELL, a citizen of the United States, residing at Chicago, in the county of Cook and State 5 of Illinois, have invented a certain new and useful Improvement in Convertible Box-Cars, of which the following is a full, clear, concise, and exact description, reference being had to the accompanying drawings, 10 forming a part of this specification.

This invention relates to improvements in convertible box cars.

In the operation of railroads, there is a constantly increasing demand for more continuous use of all rolling stock and particularly in connection with box cars. At certain seasons of the year, especially in the case of the so-called grain-carrying roads, there is a heavy demand for box cars for 15 the transportation of grains and in the intervening periods, the demand for said cars on those roads is appreciably less and large numbers of the box cars are frequently employed in other sections of the country in 20 the carrying of packaged loads or other loads which are not of a "fluid" nature. It is highly desirable that all box cars be interchangeably adapted for the carrying of either packaged loads or loads of a fluid 25 character such as grain in order to maintain such box cars constantly in productive operation. An essential characteristic of such a convertible car is that, when it is not being employed for the carrying of grain, 30 no capacity shall be lost or interference permitted with the loading or unloading of the packages, boxes or the like. Another essential characteristic of a successful convertible box car of the type indicated is that the 35 means employed to convert the car shall not be of excessive weight or excessive in cost 40 of manufacture or application.

One object of my invention is to provide a convertible box car having a simple, efficient and economical arrangement whereby the car is adapted for use either as an ordinary box car to carry so-called packaged loads without loss of carrying capacity or 45 as a car to carry bulk loads such as grain, coal, or like commodities wherein sufficient 50 of the load may be easily discharged to relieve the pressure behind the necessary inside door to permit opening of the latter.

Another object of my invention is to provide a relatively inexpensive, highly effi-

cient, and substantial arrangement for insuring a perfect grain seal around the meeting edges of the fixed part of a discharge hopper and door for closing the discharge opening.

Another object of my invention is to provide in a car having a discharge hopper, efficient and simple means for securely locking the door of the hopper in closed position combined with grain sealing means supplementary to those employed between the door and fixed parts of the hopper.

Other objects of the invention will more clearly appear from the description and claims hereinafter following.

In the drawings forming a part of this specification, Figure 1 is a side elevation of a portion of a convertible box car taken at the center thereof at the usual side door opening and in which are embodied my improvements. Fig. 2 is a horizontal, sectional view of the structure illustrated in Fig. 1 and corresponding substantially to the section line 2—2 thereof. Fig. 3 is a vertical, sectional view corresponding substantially to the section line 3—3 of Fig. 2, the section of Fig. 3 being so taken as to illustrate the farther interior side of the car. Fig. 4 is a vertical, transverse, sectional view of the car corresponding substantially to the section line 4—4 of Fig. 1. Fig. 5 is a vertical, sectional view similar to Fig. 4, but corresponding to the section line 5—5 of Fig. 1. Fig. 6 is an enlarged detail sectional view illustrating more particularly the arrangement at the meeting edges of the hopper bottom and door, said section corresponding substantially to the line 6—6 of Fig. 1. Fig. 7 is an enlarged detail sectional view illustrating more particularly the arrangement for pivotally attaching the hopper door and forming a grain seal at the point of attachment, said view corresponding to a portion of Fig. 4. And Fig. 8 is a detail section corresponding to the section line 8—8 of Fig. 4.

In said drawings, the box car is shown as having the usual side walls 10—10, with the usual side door openings 11, ordinarily placed at the center of the car. The sides 105 of each door opening are defined by vertically extending Z-bars 12—12 secured to the outer side of the side wall sheathing and posts 13—13 mounted in one of the angles 110 of the Z-bars, the arrangement being such

that notches or rabbets 14 are formed between the vertical terminal edges of the sheathing and the posts 13 as best indicated in Fig. 2, the depth of said notches equaling 5 the thickness of the side wall sheathing. The car is also provided with a fixed flooring 15, except that elongated discharge openings of rectangular form 16 are provided immediately adjacent and opposite 10 each side door opening of the car. As best seen in Fig. 4, the underframe of the car comprises channel center sills 17 and channel side walls 18, the latter having their flanges 18^a—18^a turned inwardly and preferably there is an angle iron 19 secured to 15 each side sill channel so as to secure a wider bearing for supporting the threshold 20. The underframe of the car also includes pressed diaphragms 21 extending between 20 the center sill and side sills, only those two diaphragms 21 being shown in Fig. 3 which normally come adjacent the side door openings.

In the drawings, the illustrations of my 25 improvements are confined mostly to the arrangement at one side of the car only but, as will be understood by those skilled in the art, the arrangements will preferably be duplicated on each side of the center sill 30 but for descriptive purposes, the arrangement on one side only need be set forth.

To normally close each floor opening 16 when the car is being utilized for the carrying of package freight and the like, I 35 employ a floor door 22 preferably made of planks corresponding to the usual floor planking, said planks being suitably bound by marginal metal strips 22^a—22^a and the door reinforced on its under side by a plurality of angle irons 22^b. Said door 22 is 40 preferably pivoted near its outer edge as indicated by the pivot lugs 23 at a point immediately above the upper flange 18^a of the side sill and substantially in alignment with the side wall sheathing of the car. Said door 22 is adapted to be swung upwardly 45 to a vertical position as indicated by the dotted lines 122 in Fig. 4 where it forms a partial closure for the side door opening. In this connection, it is to be observed that 50 the length of the door corresponds substantially to the distance between the vertical edges of the side wall sheathing so that said door, when in vertical position, will fit in the grooves or rabbets 14 snugly against the side door posts 13 and hence, although the door 22 will generally be made of greater thickness than the sheathing, it will project inwardly of the sheathing only a relatively 55 small distance as indicated in Fig. 4. In its vertical position, the door 22 is adapted to be held by a pair of latches 24—24 each pivotally mounted on a bracket 25 secured to the inner side of the sheathing. Each latch 60 24 slips into a recess defined by the main

part of the bracket 25 and an arm 25^a, as shown in Figs. 3 and 4. Preferably, the inner face of each arm 25^a will be beveled so as to cam or wedge the latch 24 tightly against the door 22 in holding the latter in 70 place. For convenience in lifting the door 22, it may be provided with a pair of rings 22^c—22^c, as shown in Fig. 2.

As best shown in Fig. 4, the outer edge of the door 22 when in normal horizontal position is afforded a substantial support by the top flange 18^a of the side sill. The inner edge of the door is afforded a substantial support by means of a longitudinally extending angle iron 26 which extends between and is secured at its ends to the two diaphragms 21—21, before mentioned. A supplemental support for said angle iron 26 at its center is afforded by a pressed filler plate 27 secured at its inner end to the adjacent center sill 17. Preferably, the upper flange of the angle iron 26 extends partially under the edge of the adjacent portion of the fixed floor.

As shown in the drawings, the width of the door 22 is made proximately half the distance between the side sill and the center sill for the reason that it is not advisable, ordinarily to make such a floor door extend entirely between the side sill and center sill. On this account, when the door 22 is in vertical position, it will not extend high enough to provide for the retaining of a full load of grain or other so-called fluid commodities and it is therefore advisable to provide extensions for the closure of the side doors 22. For this purpose, I provide two or more floor door extensions indicated generally by the reference characters A—A in Fig. 4. Each of said extensions A—A preferably 105 consists of a double layer of boards or planks suitably bound by metal strips and the thickness of which corresponds to the thickness of the floor door 22. Said extension boards A—A are loosely stored within the hopper, hereinafter described, and when desired for use, are applied on edge above the vertically positioned floor door and held in place by additional latches similar to those referenced 24 and heretofore described. As will be understood, the length of the extension boards A—A corresponds to the length of the door 22 and hence the same will fit within the grooves or rabbets 14 when in operative position.

The hopper which I provide on each side of the car beneath each floor door 22 may be formed of sheet metal as shown and will have substantially triangular shaped end hopper sheets 28—28 and a downwardly and outwardly sloping bottom sheet 29. The former are secured at their upper edges to the diaphragms 21 and the bottom sheet 29 at its upper edge to the angle iron 26. The end sheets 28 are inwardly deflected near 130

their top edges as indicated at 28^a—28^a in Fig. 3 so as to bring the distance between the main portions of said hopper end sheets slightly greater than the length of the floor door and door extensions A—A.

5 The hopper bottom sheet 29 is suitably braced at spaced intervals preferably by angle irons 30—30 which are run crosswise of the car and secured to the center sills and to 10 the filler plate 27, the outer ends of said angle irons 30 being downwardly bent as indicated at 30^a to conform to the slope of the hopper bottom sheet 29.

15 The discharge opening of the hopper is closed by a hopper door designated generally by the reference character B. The latter is preferably of sheet metal pressed to the desired shape and as shown, has an upper rounded or curled edge 31, a lower outwardly extended and curved edge 32 and outturned flanged side edges 33 united with the main part of the door by rounded corners 33^a. The door B is braced on its outer side by a plurality of vertically extending 20 angles 34 and by a longitudinally extending angle 35.

25 As is well known, it is necessary to provide a grain seal along all meeting edges of a door and fixed part of a hopper in order 30 to prevent leakage and avoid claims for losses against the railroads. To provide the grain seal along the upper pivoted edge of my hopper door B, I employ a longitudinally extending member designated generally 35 by the reference C, as best shown in Figs. 4 and 7. Said member C extends the full length of the door B and is of substantially inverted trough shape in cross section and comprises an upper horizontal web 36 40 adapted to be secured to the lower flange 18^a of the side sill, an outer longitudinally and downwardly extended flange 37 and an inner longitudinally and downwardly extended flange 38. Each of said flanges 37 and 38 is 45 preferably curved to conform to the curvature of the curled edge 31 of the door and so disposed that there are at least three lines of contact afforded between said curled edge 31 and the member C, one such line of contact being between the curled edge and the flange 38, another between the curled edge and the horizontal web 36 and the third between the curled edge and the flange 37. In this manner I obtain at least three lines 50 of sealing contact which are always operative regardless of the position of the door and which at the same time permit the swinging of the door about its pivotal axis as hereinbefore described. Furthermore, the 55 member C affords an unusually strong brace and protection for the relatively thin sheet metal curled edge of the door. It is obvious that the member C may be readily attached to the usual construction of car underframe 60 without modification of the latter.

To provide for the pivotal movements of the door B, I employ preferably four T-bolts each designated generally by the reference character D. Each of said bolts, as best shown in Fig. 7, has a vertically extended 70 threaded shank 39 and cylindrical horizontally extending branches 40 at its bottom, the latter loosely fitting within the curled edge 31. To allow for the swinging movements of the door, the curled edge is slotted as indicated at 75 41, where the shank 39 passes through. The shank of each bolt passes through suitable alined perforations in the member C, the lower flange 18^a of the side sill and a horizontally extending flange of an angle iron 42 80 secured to the inner side of the web of the side sill. Each T-bolt is held in position by a nut 43 and preferably lock washer 44 and locking clip 45. By employing a threaded shank on the T-bolt D, I am enabled to effect 85 any desired adjustment and desired degree of pressure between the curled edge of the door and the coöperating sealing member C.

As shown best in Fig. 8, the outturned flanges 33 on the ends or side edges of the 90 door fit within correspondingly offset flanges 133 pressed in the end hopper sheets 28 so that a grain seal is effected along these meeting edges of the door and hopper proper.

95 To provide the grain seal between the hopper bottom 29 and lower horizontally extending edge of the door B, I employ a longitudinally extending bulb angle iron 46 secured to the under side of the bottom sheet 100 29 and having its bulb 46^a thereof projecting outwardly beyond the edge of the sheet. The rounded edge of the bulb 46^a conforms to the curved flange 32 of the door B. The termini of the angle irons 30 may be riveted to 105 the flange 46^b of the bulb angle and it will be evident that the bulb angle also affords a substantial bracing for the lower edge of the hopper bottom sheet 29.

110 To hold the door B in closed position and also to supplement the seal along the lower edge of the door, I employ the following mechanism. Secured to each hopper end sheet 28 on the outer side thereof, as best shown in Fig. 5, is a bracket 47 having a 115 depending extension 48 in which is formed a bearing for a longitudinally extending shaft 49, the later being located within the angle defined by the web and flange of the bulb angle iron 46. Secured to said shaft 49 120 at spaced intervals therealong are castings 50 each of which has an outwardly extended arm 50^a with a right-angled extension 50^b, as best shown in Fig. 6. Secured to the castings 50 and within the angles defined by 125 the arms 50^a and extensions 50^b is a longitudinally extending continuous angle iron 51. As shown in Figs. 4 and 6, it is evident that the two flanges of the angle iron 51 will 130 form two continuous lines of sealing contact

with the bulb and the convexly curved flange of the door, respectively, and furthermore that flange of the angle iron 51 which engages the flange of the door will serve to 5 cam the latter snugly up against the bulb proper when the shaft is rotated to effect closure of the door. I therefore obtain a triple grain seal along the free edge of the door as well as a triple seal along the 10 hinged edge of said door, as previously described and by means which are comparatively inexpensive and simple of application and operation.

At one or both, preferably both ends, of 15 the shaft 49, I secure a lever 52 having an extension 52^a which is adapted to be engaged by the operator's foot or a clawbar to force the lever 52 downwardly so as to permit opening of the hopper door. Said 20 levers 52 are also preferably formed as indicated at 52^b so as to provide an additional point of support and connection for the angle iron 51. On its under side, each lever 52 is provided with a rounded bearing surface 52^c at the outer end of which may be formed a stop shoulder 52^d. Coöperable with each lever 52 is a locking lever 53 pivoted to the bracket 47 as indicated at 54. The lower end of the lever 53 carries an in- 25 wardly extending shoulder 53^a adapted to ride upon the cam surface 52^c and thereby force the closure mechanism to fully closed position. At its upper end, the lever 53 is formed with a curved flange 53^b slotted as 30 indicated at 55 to receive the usual lead seal which is also extended through a corresponding opening 56 provided in the peripheral flange of a pivoted locking dog 57 also mounted on the bracket 47. As will be evident, the locking dog 57 is first knocked out of engagement with the lever 53 and then the latter has its lower end pushed backwardly, thereby relieving the lever 52 and permitting opening of the hopper door.

45 I have herein shown and described what I now consider the preferred manner of carrying out my invention as applied to a convertible box car, but the same is merely illustrative since it is evident that various 50 features of the invention may be used to advantage in other types of cars. I contemplate all changes and modifications that come within the scope of the claims appended hereto.

55 I claim:

1. In a car provided with a hopper having a discharge opening, the combination with a hopper door pivoted along one edge and adapted to close said opening, said edge 60 being rounded; of a sealing member coöperable with said edge of the door extending lengthwise of the door edge and having a flat intermediate web and side flanges extending therefrom toward the door and 65 within which is oscillatably movable said

rounded edge of the door, said rounded edge having lines of contact with the inner faces of said flanges and with said web.

2. In a car provided with a hopper having a discharge opening, the combination 70 with a hopper door pivoted along one edge and adapted to close said opening, said edge being rounded; of a sealing member coöperable with said edge of the door extending lengthwise of the door edge and having a flat 75 intermediate web and side flanges diverging therefrom toward the door and within which is oscillatably movable said rounded edge of the door, said flanges being curved to conform to the curved edge of the door, 80 said curved edge of the door having lines of tangency with intervening spaces with both of said flanges and the web of said member.

3. In a car provided with a hopper having 85 a discharge opening, the combination with a hopper door pivoted along one edge, said edge being constituted by a curled section of sheet metal; and means for pivotally supporting said edge of the door, said means including a T-shaped element having a shank extending through a slot in said curled edge, the branches of the T-shaped element being of cylindrical form and co-operating with the interior of the curled 90 edge.

4. In a car provided with a hopper having a discharge opening, the combination with a hopper door pivoted along one edge, said edge having a rounded exterior surface; of means 100 for pivotally supporting said door along said edge, said means including a T-bolt adjustably secured to a fixed part of the car, the shank of said T-bolt extending through said edge of the door and the 105 branches of the T-bolt being substantially cylindrical and providing a bearing for said edge of the door.

5. In a car provided with a hopper having a discharge opening, the combination 110 with a hopper door pivoted along one edge and adapted to close said opening, said edge being rounded; of a sealing member coöperable with said edge of the door, said member being secured to a fixed part 115 of the car and extending lengthwise of said edge, said member being of substantially trough shape in cross section and within which is oscillatably mounted said edge; and means providing a pivotal connection for 120 said edge of the door, said means including a T-shaped element the shank of which extends through said rounded edge of the door, the branches of said T-shaped element being substantially cylindrical and extending 125 parallel to the edge of the door on the inner side of the rounded edge thereof.

6. In a car provided with a hopper having a discharge opening, the combination with a hopper door adapted to close said 130

- opening, said door having its pivotal edge rounded; of a sealing member coöperable with and extending lengthwise of said edge of the door, said member being secured to 5 a fixed part of the car and of substantially trough shape in cross section and fitting over said rounded edge; and means for pivotally supporting said edge of the door, including, a T-bolt having the shank thereof 10 extending through a slot in said edge of the door, said T-bolt being adjustably secured to a fixed part of the car.
7. In a car provided with a hopper having a discharge opening, the combination 15 with a hopper door having the main part thereof comprised of sheet metal, one edge of said sheet metal being curled; of a sealing member coöperable with said curled edge of the door, said member being secured to a fixed part of the car and extending lengthwise of said edge, said member being of substantially trough shape in cross section and within which is oscillatably disposed said curled edge; and a plurality of 20 T-bolts adjustably secured to fixed portions of the car, said curled edges having slots therein through which the shanks of said T-bolts extend, the branches of each T-bolt being of substantially cylindrical form and 25 30 fitting against the inner side of the curled edge.
8. In a car provided with a hopper having a downwardly inclined hopper bottom and a discharge opening, the combination 35 with a hinged hopper door adapted to close said opening; of means for forming a grain seal between the meeting edges of said door and hopper bottom, said means including a member having a bulbed edge secured 40 to the hopper bottom, said bulbed edge extending beyond the hopper bottom proper and a curved flanged edge on the door arranged to fit over said bulb when the door is in closed position; and means for holding 45 said door in closed position.
9. In a car provided with a hopper having a downwardly inclined hopper bottom and a discharge opening, the combination with a bulb angle iron secured to the lower edge 50 of said hopper bottom with the bulb thereof projecting beyond the hopper bottom; of a hinged hopper door adapted to close said opening, said door having its lower edge formed with a curved flange adapted to fit 55 over said bulb; and means for holding said door in closed position.
10. In a car, the combination with a hopper including a downwardly inclined hopper bottom; of a hopper door hinged along 60 its upper edge and adapted to close the hopper opening, the meeting edges of said door and hopper bottom having coöperating fitting sections projecting outwardly from the planes of both the door and the hopper bottom; and mechanism for clamping said fit- 65 ting sections together including, a member oscillatable about an axis parallel and adjacent to said fitting sections, said member extending lengthwise of said fitting sections and formed to wedge thereover when moved to operative position.
11. In a car, the combination with a hopper including a downwardly inclined hopper bottom; of a hopper door hinged along its upper edge and adapted to close the hopper opening, the meeting edges of said door and hopper bottom having coöperating fitting sections projecting outwardly from the planes of both the door and the hopper bottom; and mechanism for clamping said fitting sections together including, a member oscillatable about an axis parallel and adjacent to said fitting sections, said member extending lengthwise of said fitting sections and formed to wedge thereover when moved to operative position, said member being of continuous angle formation.
12. In a car, the combination with a hopper including a downwardly inclined hopper bottom; of a hopper door hinged along its upper edge and adapted to close the hopper opening, the meeting edges of said door and hopper bottom having coöperating fitting sections projecting outwardly from the planes of both the door and the hopper bottom; a shaft rotatably mounted about an axis parallel to the lower edge of the hopper bottom and beneath the hopper bottom; a plurality of arms rigidly carried by said shaft; and an angle iron mounted on said arms, said angle iron extending lengthwise of the fitting sections of the door and hopper bottom and adapted to wedge over the latter when the shaft is swung to closed position.
13. In a car, the combination with a hopper having a downwardly inclined hopper bottom; of a bulb angle iron secured to and extending lengthwise of the lower edge of the hopper bottom with the bulb projecting beyond the hopper bottom; a hopper door pivotally mounted along its upper edge, the lower edge of said door having a curved flange adapted to fit over said bulb; a shaft extending parallel to the bulb angle iron and mounted within the angle thereof; and an angle iron carried by said shaft and extending lengthwise of the meeting edges of the door and hopper bottom, said angle iron being arranged to fit over said bulb and curved flange when in operative position.
14. In a car, the combination with a hopper having a downwardly inclined hopper bottom; of a hopper door pivoted along its upper edge adapted to close the opening of the hopper; and mechanism for holding said door in closed position including, a shaft, a lever rigidly secured to said shaft and having a wedge-camming surface, a piv-

totally mounted lock lever having a coöperating wedge-camming shoulder engageable with said surface to force said first named lever positively in a closing direction, and 5 a locking dog coöperable with said lock lever.

15. In a car, the combination with a hopper having a downwardly inclined hopper bottom and vertical ends; of a hopper door pivotally mounted to swing about its upper edge, the lower edge of the door and the lower edge of the hopper bottom having coöperating grain-sealing means; a shaft extending lengthwise of the hopper bottom parallel to its lower edge; bearing 10 brackets for said shaft secured to the outer faces of the hopper ends; an angle iron extending parallel to said shaft and rigidly supported thereby, said angle iron being adapted to fit over the grain-seal-forming 15 means of the door and hopper bottom; a lever secured to said shaft at one end thereof and having a cam surface; a lock lever pivotally mounted on one of said brackets adjacent said first named lever and having 20 a cam shoulder coöperable with the cam surface of the first named lever; and a locking dog coöperable with said locking lever.

16. In a car, the combination with a hopper having a downwardly inclined hopper bottom sheet and a bulb angle iron extending along and secured to the lower edge of said bottom sheet; of a hopper door having a rounded upper edge; a grain-sealing member rigidly attached to the car body and coöperable with said rounded edge of the door, said sealing member being of substantially trough shape in cross section and fitting over said rounded edge, the lower edge of said door having a curved flange arranged to fit over the bulb edge of said bulb angle iron; and means for locking said door in closed position.

17. In a car, the combination with a hopper having a downwardly inclined hopper

bottom sheet and a bulb angle iron extending along and secured to the lower edge of said bottom sheet; of a hopper door having a rounded upper edge; a grain-sealing member rigidly attached to the car body and coöperable with said rounded edge of the door, 45 said sealing member being of substantially trough shape in cross section and fitting over said rounded edge, the lower edge of said door having a curved flange arranged to fit over the bulb edge of said bulb angle iron; a shaft oscillatably mounted in the angle of said bulb iron; an angle iron rigidly carried by said shaft and extending parallel thereto, said angle iron fitting over 50 said curved flange and bulb when in operative position; and means for locking said shaft in operative position.

18. In a car provided with a hopper, having a discharge opening, the combination with a hopper door adapted to swing about 55 its upper edge and to close said opening, said edge being rounded; of a sealing member coöperable with said edge of the door and extending lengthwise thereof, said member having a horizontal upper flat web and 60 downwardly extending flanges along each edge of said web, the rounded edge of the door fitting within the flanges and web of said member; fixed means on the car to which said member is secured; and means 65 for maintaining said rounded edge of the door in operative relation with said member, said means including an element having a shank extending through a slot in said rounded edge, said shank extending also 70 through the web of said member.

In witness that I claim the foregoing, I have hereunto subscribed my name this 21st day of February, A. D. 1921.

ARGYLE CAMPBELL.
